RESTRAINT DEVICE

Ole K. Kjolseth, Erie, Pa., assignor to General
Electric Company, a corporation of New York

Application August 26, 1937, Serial No. 161,049

6 Claims. (Cl. 105—199)

My invention relates to lateral restraint or centering devices for railway trucks for restraining small oscillatory movements or lateral displacements of the trucks with respect to the vehicle frame and for permitting free pivotal movement thereof when the railway vehicle traverses a curve in the track.

In railway vehicles, the vehicle frame usually is supported on a plurality of trucks, and some arrangement generally is provided for permitting a limited amount of lateral pivotal movement of the truck frames relative to the vehicle frame in order to minimize the pressure exerted by the flanges of the wheels against the rails when the vehicle is passing around a curve. It is also desirable that lateral oscillations of the trucks should be restrained under normal operating conditions and that the truck should be maintained in substantial alignment with the vehicle frame, but the centering force should act only for small lateral displacements, and when the vehicle enters a curve in the track the lateral pivoting of the trucks should not be restrained. It is desirable, therefore, that the lateral restraint or centering device should exert a predetermined restraining force for a predetermined small range of lateral displacement from longitudinal alignment of the trucks and the vehicle frame, and substantially no restraining force for any further lateral displacement therebetween.

An object of my invention is to provide an improved lateral restraint or centering device which will resiliently center laterally movable or oscillatable vehicle trucks relative to the vehicle frame, and restrain small lateral displacements or oscillations of the trucks.

Further objects and advantages of my invention will become apparent and my invention will be better understood from the following description referring to the accompanying drawings, and the features of novelty which characterize my invention will be pointed out with particularity in the claims annexed to and forming part of this specification.

In the drawings, Fig. 1 is a side elevation of a locomotive embodying my invention; Fig. 2 is an elevation, taken along line 2—2 of Fig. 1 transversely of the locomotive and partly in section, of an embodiment of my improved lateral restraint mechanism; Fig. 3 is an end view, partly in section, of the restraint device shown in Fig. 2; Fig. 4 is a plan view, partly in section, of the device shown in Fig. 2 in its central operating position; Fig. 5 is a plan view of the device shown in Fig. 2 showing the relation of the

parts when the locomotive is in a curve in the track; Fig. 6 is an elevation, taken along line 6—6 of Fig. 1 transversely of the locomotive and partly in section, of another embodiment of my improved restraint device; Fig. 7 is a plan view, partly in section, of the device shown in Fig. 6 in its central operating position on straight track; Fig. 8 is a plan view of the device shown in Fig. 6 showing the relation of the parts when the locomotive is in a curve in the track; and Fig. 9 is an end view, partly in section, of the device shown in Fig. 6.

Referring to the drawings, an electric locomotive having a frame including a superstructure 10 is pivotally supported by center bearings or pins 11 and 12 on main truck frames 13 and 14, respectively. To facilitate traversing curves in the track, the outer end of each of the main truck frames 13 and 14 is supported upon an auxiliary truck 15 having a relatively small distance between axles. The auxiliary trucks 15 are of the double axle type provided with wheels 16 mounted on axles 17 journaled in journal boxes 18 which support the auxiliary truck frames 15.

The locomotive is propelled by driving wheels 19 through axles 20 driven by electric motors 21, and the axles are journaled in journal boxes 22 on which the frames of the main trucks 13 and 14 are supported. Irregularities in the truck tend to produce oscillations of the trucks about the center pins 11 and 12 which pivotally support the locomotive frame, and it is desirable that these oscillations should be restrained in order to provide a smooth operation of the vehicle. These oscillations of the trucks produce lateral displacements between the inner ends of the trucks relative to the locomotive frame, and these oscillations can be greatly reduced or limited by providing a lateral restraint or centering device which will maintain substantial alignment of the trucks and the locomotive frame.

It is desirable that the restraint device should not restrain the lateral displacement of the end frames of the trucks beyond a predetermined range, as it is necessary that the trucks pivot about their connections to the locomotive frame when the locomotive traverses a curve in the track. Furthermore, since the auxiliary truck 15 at the trailing end of the locomotive enters a curve in the track after the main driving wheels 19 of the trailing truck 13 have already entered the curve, this auxiliary truck does not provide any guiding force for guiding the main truck 13 into the curve during forward operation of

the locomotive, and it is desirable that this guiding force should be applied to the forward end of the truck 13 as it enters a curve.

In order to provide a guiding force and to prevent oscillation of the trailing truck 13, I provide a lateral restraint device adjacent the forward or inner end of the trailing truck and pivotally secure a follower arm 23 to the truck frame 13 adjacent a corner on the inner end thereof through a ball 24 and socket connection 25. This universal joint is pivotally carried by a pin 26 extending through the ball 24 and into bearings 27 on flanges 28 and 29 formed on the truck frame 13. The follower arm 23 is provided with a pair of similar oppositely disposed and spaced apart cam surfaces of varying curvature each having a central inwardly curved or tapered section 30 and straight parallel end sections 31 on each side of the tapered portions 30. These cam surfaces are joined by a web 32 and reinforced by cross-ties 33. The follower arm is arranged to extend transversely of the truck frame 13 and the locomotive frame 34 and between a pair of rollers 35 which are rotatably supported on spindles 36 and carried by cross-head guides 37. The cross-head guides 37 slidably engage bearing guide surfaces 38 in a casing 39 secured to a bracket 40. The bracket 40 is provided with an upper supporting plate 41 which is attached by bolts 42 to the under sill 43 of the locomotive frame 34. The outer ends 44 of each of the cross-head guides 37 engage a follower plate 45 which is resiliently biased inwardly by two sets of springs 46, 47, and 48. These springs are held under compression between the follower plates 45 and spring seats 49 by through bolts 50, which adjustably secure together the spring seats 49 and the bracket 40 and extend through openings 51 in the follower plates 45. In this manner, the rollers 35 are carried by the locomotive frame 34 in relatively movable relation to each other and to the locomotive frame, and are resiliently biased toward each other by the springs 46, 47, and 48 into engagement with the cam surfaces of the follower arm 23. As shown in Figs. 2 and 3, a portion 52 of each of the cam surfaces adjacent the center of the tapered portions 30, where the web 32 is the narrowest, does not conform to the cylindrical surface of the rollers 35, but has a sharper curvature, so that the rollers 35 do not seat in this smaller curvature portion 52 of the cam surfaces, but engage the cam surfaces at spaced points 53 on each side of these smaller curvature portions 52 of the cam surfaces.

When the locomotive passes over irregularities in the track which tend to cause the trucks to oscillate and produce lateral displacements between the ends of the truck frames and the locomotive frame, the rollers 35 tend to pivot about one or the other of the points 53 on each side of the center of curvature of the cam surfaces, and this leverage effectively utilizes the sets of springs to restrain oscillations of the main truck 13 to small limited lateral movements with respect to the locomotive frame, and this maintains substantially longitudinal alignment of the truck and the locomotive frame during normal operation along a straight track. When the locomotive enters a curve, the locomotive frame 34 tends to be displaced laterally with respect to the forward or inner end of the trailing truck 13, and the rollers 35 roll along the inclined or tapered portions 30 of the cam surface, thereby moving outwardly and further compressing the

springs 46, 47, and 48. This produces a restraining force on the follower arm 23, which is transferred to the truck frame as a guiding force to guide the truck into the curve in the track. When the truck is in the curve, it will pivot about the center pin 11 and produce a relatively large lateral displacement between the truck frame 13 and the locomotive frame 34 causing the rollers 35 to roll out over the straight portions of the cam surfaces, as shown in Fig. 5, on which they roll with substantially no restraint. The restraining force of the device may be adjusted by varying the compression of the springs 46, 47, and 48 by adjusting the position of the nuts 54 on the through bolts 50. In this manner, the lateral restraint device provides a variable restraining force which is a predetermined initial restraining or centering force for small lateral displacements between the truck frame and the locomotive frame, and another predetermined restraining force for a predetermined range of relative lateral displacement of these frames, and substantially no restraining force for any further lateral displacement therebetween.

The auxiliary truck 15 at the forward end of the main truck 14 supports the forward end of the main truck, and when the locomotive enters a curve in the track, the auxiliary truck 15 exerts a guiding force upon the truck 14 which tends to pivot the truck about the center pin 12, and thereby guides the truck into a curve. With this arrangement, it is not necessary to provide a lateral restraint device which exerts as much restraining force upon the inner end of the leading truck 14 as the restraining force exerted by the lateral restraint device on the inner end of the trailing truck 13. I, therefore, provide a lateral restraint device of lighter construction adjacent the rear or inner end of the leading truck 14 and secure a follower arm 55 to the truck frame 14 adjacent a corner on the inner end thereof through a ball 56 and socket connection 57. This universal joint is pivotally carried by a pin 58 extending through the ball 56 and into bearings 59 on flanges 60 and 61 formed on the truck frame 14. The follower arm 55 is provided with a pair of spaced apart cam surfaces 62 and 63 of varying curvature, which are supported by a web 64 and reinforced by cross ties 65. The cam surface 63 is straight throughout its length, and the major portion of the cam surface 62 also is straight and parallel to the cam surface 63 throughout most of its length, and is provided with an indented or curved portion 66 at about the central portion thereof. The follower arm 55 is arranged to extend transversely of the truck frame 14 and the locomotive frame 34 and between a pair of rollers 67 and 68 which are rotatably supported on spindles 69 and 70, respectively. The spindle 69 is carried by a cross-head guide 71 within casings 72 which are secured to brackets 73. The lower spindle 70 is in the form of a bolt, and is rigidly secured by a nut 74 to the lower end of the casings 72 and the brackets 73. The brackets 73 are secured by welding to an upper supporting plate 75 which is bolted by bolts 76 to the under sill 43 of the locomotive frame 34. The upper end 77 of the cross-head guide 71 engages a follower plate 78 which is resiliently biased downwardly by a pair of springs 79. These springs are held under compression between spring seats formed on the follower plate 78 and spring seats formed on another follower plate 80 by through bolts 81, 75

which adjustably secure together the follower plate 80 and the supporting plate 75 of the brackets 73. These bolts 81 extend through openings 82 formed in the follower plate 78 and permit free relative axial movement of the plate with respect to the bolts. In this manner, the upper roller 67 is carried by the locomotive frame 34 in relatively movable relation to the locomotive frame 34 and the lower roller 68, and is resiliently biased toward the lower roller 68 by the springs 79 into engagement with the upper cam surface 62 of the follower arm 55. As shown in Figs. 6 and 9, the central portion of the curved cam surface 66 does not conform to the cylindrical surface of the roller 67, but has a sharper curvature so that the roller 67 does not seat in the central portion of the curved section 66, but engages the cam surfaces at spaced points 83 on each side of this section of smaller curvature.

When the locomotive passes over irregularities in the track and it tends to cause the trucks to oscillate and produce lateral displacements of the trucks with respect to the locomotive frame, the roller 67 will roll in the grooved portion 66 and pivot about one or the other of the points 83 of the curved cam surface 66 and effectively restrain oscillation of the main truck 14 to a small limited movement with respect to the locomotive frame, and thus maintain substantial longitudinal alignment of the truck with the locomotive frame during normal operation along a straight track. The lower roller 68 merely rolls along the lower straight cam surface 63 and facilitates the operation of the device, but does not exert any restraining force at any time. When the locomotive enters a curve, the truck 14 will pivot about the center pin 12 and produce a relatively large lateral displacement of the ends of the truck frame with respect to the locomotive frame. This causes the roller 67 to roll out of the grooved portion 66 of the upper cam surface 62 against an initial restraint and onto one of the straight portions on either side of the curved section 66, as shown in Fig. 8, where the roller 67 rolls with substantially no restraint upon the follower arm 55. The restraining force of the device may be adjusted by varying the compression of the springs 79 by adjusting the position of the nuts 84 on the through bolts 81. In this manner, the lateral restraint device provides a variable restraining force which is a predetermined initial restraining or centering force for a small range of lateral displacement of the end of the truck frame with respect to the locomotive frame and substantially no restraining force for any further lateral displacement therebetween.

While I have illustrated and described particular embodiments of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States, is:—

1. A locomotive or car having a frame, a truck having a support for said locomotive or car frame, a roller carried by said frame, a follower arm having a cam extending transversely of said frame and pivotally carried by said truck, means including a spring for biasing said roller into engagement with said cam, and means including

a cam surface of varying curvature carried by said cam for providing a variable restraining force to relative lateral displacement between said truck and said frame.

2. A locomotive or car having a frame, a truck having a truck frame arranged to support said locomotive or car frame, a lateral restraint device arranged adjacent the inner end of said truck and including a roller carried by one of said frames, a cam pivotally carried by the other of said frames and extending transversely of said frames, means including a spring for biasing said roller into engagement with said cam, and means including a cam surface carried by said cam and cooperating with said roller for providing a restraining force over a small range of relative lateral displacement between said frames and for providing substantially no restraining force to any further relative lateral displacement therebetween.

3. A locomotive or car having a frame, a truck having a truck frame arranged to support said locomotive or car frame, a lateral restraint device including a plurality of rollers carried by one of said frames, a spring arranged to bias said rollers toward each other, a cam pivotally carried by the other of said frames and extending transversely of said frames, and means including a cam surface arranged between said rollers for providing a restraining force over a predetermined range of relative lateral displacement between said frames and for providing substantially no restraining force to any further lateral displacement therebetween.

4. A locomotive or car having a frame, a truck having a frame arranged to support said locomotive or car frame, a lateral restraint device arranged adjacent the inner end of said truck and including a plurality of rollers, means for rotatably supporting said rollers on one of said frames in relatively movable relation to each other, a cam pivotally carried by the other of said frames and extending transversely of said frames, said cam having a cam surface arranged between and to cooperate with said rollers, and means including a spring biasing said rollers into engagement with said cam surface for providing a restraining force over a small range of relative lateral displacement between said frames and for providing substantially no restraining force to any further relative lateral displacement therebetween.

5. A locomotive or car having a frame, a truck having a truck frame arranged to support said locomotive or car frame, a lateral restraint device arranged adjacent the inner end of said truck and including a plurality of rollers carried by one of said frames, a follower arm having a universal connection to the other of said frames and extending transversely of said frames, said follower arm having a pair of similar cam surfaces arranged to extend between and to cooperate with said rollers, and means including a spring biasing said rollers into engagement with said cam for providing a restraining force over a predetermined range of relative lateral displacement between said frames and for providing substantially no restraining force to any further relative lateral displacement therebetween.

6. A locomotive or car having a frame, a truck having a frame arranged to support said locomotive or car frame, a lateral restraint device including a plurality of rollers, means including a guide for supporting each of said rollers on one of said frames in relatively movable relation to each other and to said frame, a follower arm hav-

ing a universal connection to the other of said frames and extending transversely of said frames, said follower arm having a plurality of similar cam surfaces arranged to extend between and to cooperate with said rollers, and means including a spring biasing said rollers into engagement with

said cam surfaces for providing a restraining force over a predetermined range of relative lateral displacement between said frames and for providing substantially no restraining force to any further lateral displacement therebetween.
